TRAPLESS STEAM CONDENSATE SYSTEM

Alva Gleason Arbogast, Charleston, W. Va.

Application November 1, 1957, Serial No. 693,944

7 Claims. (Cl. 237—9)

This invention relates to steam utilization systems, and more particularly to a method and means for removing steam condensate from steam-using equipment and is a continuation-in-part application of my pending application Serial No. 683,901, filed September 13, 1957.

A main object of the invention is to provide a novel and improved system for rapidly removing steam condensate from steam-utilizing equipment of the type employing the latent heat of steam for the operation thereof, the system involving simple components, requiring no steam traps, and providing a higher rate of heat transfer to a steam-utilizing device that can be attained in a system employing steam traps.

A further object of the invention is to provide an improved system for rapidly removing steam condensate from steam utilizing equipment, the system being arranged so that it provides positive control of condensate drainage, thereby permitting a controlled amount of steam to be withdrawn with the condensate and assuring complete and rapid disposal of the steam condensate.

A still further object of the invention is to provide an improved system for rapidly removing steam condensate from steam-utilizing equipment, the system involving relatively inexpensive components, being reliable in operation, and assuring maximum rate of heat transfer to the equipment, whereby the equipment may be efficiently employed for performing process work requiring heat transfer.

A still further object of the invention is to provide an improved method and means for rapidly removing steam condensate from steam-utilizing equipment of the type employing the latent heat of steam, the means being arranged so that it requires minimum maintenance, has high sensitivity to the presence of live steam in the condensate drain line, responds immediately to the presence of condensate in the drain line to rapidly remove the condensate, and is especially useful in process work, such as plastic molding, air heating at high temperatures, contact heating of moving material over a heated platen or roll, or the like, or in other operations involving the use of extremely high steam pressures, the apparatus being characterized by the absence of steam traps and therefore being relieved of maintenance problems ordinarily associated with the use of extremely high pressure steam traps.

A still further object of the invention is to provide an improved system for rapidly removing steam condensate from steam-utilizing equipment, the system providing close control over the utilization of the steam and being arranged so that it prevents excessive steam waste.

Further objects and advantages of the invention will become apparent from the following description and claims, and from the accompanying drawings, wherein:

Figure 1 is a schematic view of a steam-utilizing system constructed and arranged in accordance with the present invention.

Figure 2 is an enlarged longitudinal vertical cross sectional view taken through the condensate-sensitive impulse amplifying device employed in the system of Figure 1.

Referring to the drawings, Figure 1 illustrates a typical

2

steam-utilizing system arranged in accordance with the present invention. Designated at 11 is a high pressure steam line leading from a source of high pressure steam, said steam line being connected to a steam header 12 through a manually controlled valve 13. Designated at 14 is an exhaust header which is connected to the condensate drainage line 15 leading to a suitable vented condensate receiver, not shown.

Designated at 16 are a plurality of steam-utilizing devices, for example, heating devices employed in process work, said devices utilizing the latent heat of the high pressure steam admitted thereto. Thus, the heat transfer devices 16 are supplied with live steam from the header 12 through inlet conduits 17, as shown in Figure 1, the exhaust steam leaving the devices 16 through discharge conduits 18. The discharge conduits 18 are connected to the exhaust steam header 14 through respective restriction devices 19, similar to those shown and fully described in applicant's copending application Serial No. 683,901, filed September 13, 1957. Thus, the restriction devices 19 comprise sleeve members provided with internal transverse walls, each formed centrally with a restriction, defining an orifice, the orifice being calibrated or dimensioned to handle the maximum quantity of condensate that its associated steam utilizing device can produce in a given period of time under a predetermined pressure differential across the orifice.

The aforesaid pressure differential across the orifices in the restriction devices 19 is controlled by a pressure differential-responsive valve, designated generally at 23, and fully described in the above-mentioned copending application, Serial No. 683,901, entitled "Trapless Steam Condensate System." The valve 23 is connected in the condensate drain line 15 and is controlled in accordance with the difference in pressures in the steam line 11 (and steam header 12) and the condensate drainage line 15.

The pressure-responsive valve 23 is of the normally open type and includes a diaphragm housing 25 containing a diaphragm and having respective chambers 39 and 40 above and below the diaphragm thereof. The diaphragm is connected to a plunger valve provided in the plunger housing 26, spring means, not shown, being provided to bias the plunger of the valve to an open position with respect to its seat. A conduit 41 connects the lower chamber 40 to the end of the high pressure steam header 12, whereby the high pressure steam in header 12 acts against the spring means of the valve and tends to close the valve in accordance with the supply steam pressure. Thus, increase in pressure in line 11 normally acts to close the valve, since it acts against the valve spring.

A conduit 42 connects the upper diaphragm chamber 39 to the intermediate portion of a pressure impulse amplifying device 43 provided in the condensate drainage line 15 between the valve 23 and the exhaust header 14. Thus, the low pressure steam in the exhaust header 14 flows through the line 15 to the device 43 and is transmitted to the upper diaphragm chamber 39 through the conduit 42, acting against the diaphragm and thus supplementing the spring force of the valve plunger, whereby the valve is opened in accordance with the steam pressure in the drainage conduit 15, the net force opposing the spring being therefore the difference between the supply steam pressure and the pressure of the steam in the drainage conduit 15.

The pressure impulse amplifying device 43 comprises a main conduit section 50 connected in the condensate discharge line 15 and contains a nozzle member 51 having the reduced discharge spout portion 52 located substantially axially in the body 50 and discharging downstream, namely, toward the condensate receiver. The conduit 42 is connected to the intermediate portion of the body 50 at a point forwardly adjacent to the discharge spout 52,

as is clearly shown in Figure 2. Conduit 52 is provided with the Pitot tube 60 which is located forwardly adjacent to the discharge spout 52 and faces said discharge spout, namely, faces upstream, as shown in Figure 2. Thus, the Pitot tube 60 is located relatively close to the discharge spout 52 and is in a position to receive condensate in motion discharging from the nozzle member 51.

From the above description it will be apparent that the total pressure on the impulse line 42 will be the sum of the static pressure in the body 50 of the pressure impulse amplifying device 43 plus the impulse pressure of the moving condensate and steam discharging from the spout 52 and being received in the Pitot tube 60.

In the absence of condensate, the valve 23 will be regulated only in accordance with the pressure differential between the supply steam in header 12 and the exhaust steam in the drainage conduit 15. However when steam condensate is present in the line 15, the condensate physically strikes the Pitot tube 60, causing an increase in the effective pressure in conduit 42 which is above the normal static pressure in the body 50 of device 43. This acts to assist the valve spring and to open the valve 23 to a degree beyond its normal position, thus lowering the pressure in conduit 15 to further increase the differential pressure across the orifices in the devices 19, thus producing a further increase in flow which causes a still further increase in the impact pressure of the condensate engaging the Pitot tube 60, because of the increased velocity of the condensate. This action continues until the valve 23 is wide open, if necessary. The exaggerated opening of valve 23 causes all the condensate to be quickly blown from the equipment, after which steam, unaccompanied by condensate, will begin to exhaust from the flow-accelerating nozzle 51. The density of steam, as compared with water, is so low that it does not develop any substantial impact pressure on the Pitot tube 60. This causes the pressure in line 42 to drop back to the static pressure in the body 50, whereby normal operation of the valve 23 is resumed.

Therefore, the presence of condensate in liquid form in the drainage line 15 will cause the valve 23 to be opened beyond the amount which it would ordinarily open, and if necessary will cause valve 23 to be completely opened, until the liquid condensate is completely blown out of line 15. As soon as the liquid condensate has been eliminated, the valve automatically resumes its normal condition, wherein the valve is opened to a degree in accordance only with the difference in steam pressures between supply header 12 and condensate exhaust line 15.

It will be noted that the impulse pressure on the Pitot tube 60 is the sum of the pressure of the steam discharging from the spout 52 and any liquid condensate which may be present therein. The density of the liquid condensate is much greater than that of the steam, and therefore the impact pressure developed thereby will quickly cause valve 23 to open so as to clear out the liquid condensate from the drainage line 15.

As described in applicant's copending application Serial No. 683,901, the calibrated orifices in the restriction devices 19 are employed in place of steam traps and their flow capacity is controlled by the difference in pressure across the orifices, as set up by the pressure differential-responsive control valve 23, in combination with the calibrated orifices. Positive control of condensate drainage is provided by the adjustment of the valve 23, as above explained, which permits a controlled amount of steam to be withdrawn, along with any condensate developing therein, the condensate being quickly eliminated by the action of valve 23 and Pitot tube 60. Therefore complete discharge of the steam condensate is assured and maximum rate of heat transfer in the devices 16 is obtained.

The invention is especially useful in process work em-

ploying the latent heat of steam in the devices 16, and wherein condensate is likely to develop.

While a specific embodiment of an improved trapless steam condensate system has been disclosed in the foregoing description, it will be understood that various modifications within the spirit of the invention may occur to those skilled in the art. Therefore, it is intended that no limitations be placed on the invention except as defined by the scope of the appended claims.

10 What is claimed is:

1. In a system of the character described, a source of high pressure steam, a condensate drainage line, a steam utilizing device having an intake conduit and an exhaust conduit, means connecting said intake conduit to said source, means connecting said exhaust conduit to said condensate drainage line and including a restriction, a pressure-responsive valve in said condensate drainage line, means acting to open said valve to a degree in accordance with the difference in pressures of said source and said condensate drainage line, and means to open said valve beyond said degree responsive to the presence of condensate flowing in said drainage line.
2. In a system of the character described, a source of high pressure steam, a condensate drainage line, a steam utilizing device having an intake conduit and an exhaust conduit, means connecting said intake conduit to said source, means connecting said exhaust conduit to said condensate drainage line and including a restriction, a pressure-responsive valve in said condensate drainage line, a nozzle in said drainage line directed downstream therein, said valve being provided with a diaphragm chamber containing a diaphragm, means acting to open said valve to a degree in accordance with the difference in pressures on opposite sides of said diaphragm, respective conduits connecting the chambers on opposite sides of the diaphragm respectively to said source and the drainage line downstream from said nozzle, and a Pitot tube connected to the drainage line conduit and facing said nozzle, whereby to open said valve beyond said degree responsive to the presence of condensate flowing in said drainage line.
3. In a system of the character described, a high pressure steam line, a steam-utilizing device having an intake conduit and an exhaust conduit, means connecting the intake conduit to the steam line, a condensate drainage line, conduit means connecting said exhaust conduit to said drainage line, a nozzle element mounted in said drainage line and defining a restriction therein, a pressure-responsive valve mounted in said drainage line downstream from said nozzle, means controlling the degree of closing of said valve in accordance with the difference in steam pressures between the steam line and the portion of the drainage line between said nozzle and the valve, and means opening the valve independently of said difference in steam pressures responsive to the presence of condensate discharging from said nozzle.
4. In a system of the character described, a high pressure steam line, a steam-utilizing device having an intake conduit and an exhaust conduit, means connecting the intake conduit to the steam line, a condensate drainage line, conduit means connecting said exhaust conduit to said drainage line, a nozzle element mounted in said drainage line and defining a restriction therein, a pressure-responsive valve mounted in said drainage line downstream from said nozzle, means acting to close the valve responsive to the steam pressure in said high pressure line, means acting to open the valve in accordance with the steam pressure in the portion of the drainage line between said nozzle and the valve, and means acting to further open said valve responsive to the presence of condensate discharging from said nozzle.
5. In a system of the character described, a high pressure steam line, a steam-utilizing device having an intake conduit and an exhaust conduit, means connecting the intake conduit to the steam line, a condensate drainage

line, conduit means connecting said exhaust conduit to said drainage line, a nozzle element mounted in said drainage line and defining a restriction therein, a pressure-responsive valve mounted in said drainage line downstream from said nozzle, means acting to close the valve responsive to the steam pressure in said high pressure line, means acting to open the valve in accordance with the steam pressure in the portion of the drainage line between said nozzle and the valve and including a conduit connecting said portion to the valve, and means comprising a Pitot tube in said portion facing the outlet of said nozzle and connected to said last-named conduit and acting to further open said valve responsive to the presence of condensate discharging from said nozzle.

6. In a system of the character described, a high pressure steam line, a steam-utilizing device having an intake conduit and an exhaust conduit, means connecting the intake conduit to the steam line, a condensate drainage line, conduit means connecting said exhaust conduit to said drainage line, a restriction in said last-named conduit means, a nozzle element mounted in said drainage line and defining a further restriction therein, a pressure-responsive valve mounted in said drainage line downstream from said nozzle, means controlling the degree of closing of said valve in accordance with the difference in steam pressures between the steam line and the por-

tion of the drainage line between said nozzle and the valve, and means opening the valve independently of said difference in steam pressures responsive to the presence of condensate discharging from said nozzle.

- 5 7. In a system of the character described, a high pressure steam line, a steam-utilizing device having an intake conduit and an exhaust conduit, means connecting the intake conduit to the steam line, a condensate drainage line, conduit means connecting said exhaust conduit to said drainage line, a restriction in said last-named conduit means, a nozzle element mounted in said drainage line and defining a further restriction therein, a pressure-responsive valve mounted in said drainage line downstream from said nozzle, means acting to close the valve responsive to the steam pressure in said high pressure line, means acting to open the valve in accordance with the steam pressure in the portion of the drainage line between said nozzle and the valve and including a conduit connecting said portion to the valve, and means comprising a Pitot tube in said portion facing the outlet of said nozzle and connected to said last-named conduit and acting to further open said valve responsive to the presence of condensate discharging from said nozzle.
